UNITED STATES PATENT OFFICE.

WILLIAM F. HAMPTON AND CHARLES W. HAMPTON, OF WAYNESBORO, TENNESSEE, ASSIGNEES OF ONE-THIRD TO ROBERT A. HAGGARD, OF WAYNESBORO, TENNESSEE.

RAIL.

1,025,913.

Specification of Letters Patent.

Patented May 7, 1912.

Application filed September 7, 1911. Serial No. 648,121.

To all whom it may concern:

Be it known that we, WILLIAM F. HAMPTON and CHARLES W. HAMPTON, citizens of the United States, residing at Waynesboro, 5 in the county of Wayne and State of Tennessee, have invented certain new and useful Improvements in Rails, of which the following is a specification, reference being had to the accompanying drawings.

10 This invention relates to rails and more particularly to a particular form of rail and switch.

The object of this invention is to provide a rail which can be readily taken apart 15 without disturbing the adjacent rails, and also to provide a switch which will be limited in the number of its working parts, and arranged so that it can be readily repaired and inspected whenever the same is desirable.

Other objects of this invention will become apparent as it is more fully set forth.

In the accompanying drawings which illustrate by way of example the embodiment 25 of this invention, Figure 1 represents a plan view of a railway track embodying this invention; Fig. 2 is a sectional view along the line 2—2 of Fig. 1; Fig. 3 is a view in elevation, partly in section along the line 3—3 of Fig. 1; and Figs. 4 and 5 are details of a perforated form of rail used in connection with this invention.

Similar reference characters refer to similar parts throughout the drawings.

35 In the construction shown in the drawings, 1 represents the main rails of a track at a railway crossing, which are mounted on sleepers and the road bed of the track in the usual manner. The rail 2 joining the inner rails of the track is preferably mounted on a pivot 3, that permits said rail to rotate slightly thereon and come into engagement with the respective rail, upon which it is desired to direct the train as it 40 comes along the tracks. This rail can be of any suitable length, and of any desirable shape, but has its outer end portions provided with dove-tailed slots 4, so that dove-tailed plates 5, which are mounted on the road bed in any suitable manner, will slide readily therein. It will be noticed that this switch is alternately a part of the respective rail, of the track to which it is connected, that is, on some occasions it is 45 a part of the side track, and at other times

a part of the rail of the main track, as is clearly indicated in the drawings. It is of course understood that the inner rails of the tracks must be cut away so as to permit of ready joining of the rail 2, when the same is 60 placed in alinement therewith.

At the points of the crossing, the switch preferably consists of a pair of hinged rails 6. The hinges are disposed so as to permit the rails to come into alinement with 65 the respective rails of the track into which the train is to be guided. The hinges 7 are preferably disposed at the single track portion of the tracks, or that portion of the rails corresponding thereto. The outer portions of the hinged members 6 are provided with dove-tailed grooves 8, therein and adapted to slide on the dove-tailed plates 9 in a manner similar to that of the rail 2.

A suitable transmission 10 connects the rail 75 2 and the hinged members 6, so that these two portions of the track will be actuated together. This transmission preferably consists of a cable 11 that passes over suitable pulleys 12 and connects with both ends of 80 the rail 2, and an arm 13 suitably connected to the rail portions 6 and arranged to actuate in connection with the cable 11. A suitable handle 14 is provided on the upper portion of a drum 15 that is suitably connected 85 to the arm 13 and the rope 11 and serves as a means for moving the rails together. Suitable sections of rails 16 are disposed between the rail part 2 and the movable sections 6 as indicated in the drawings, and 90 are suitably cut to come into engagement with the parts in question when the same are actuated to come into alinement therewith.

The preferable form of rail used in this 95 device as shown in Fig. 3, consists of a standard rail form that has its end portions alternately provided with a tongue 17, and a groove for the same 18, together with the essential masses of metal to make the same.

100 The general action of the switch is so apparent as to not need any further description, except that it may be noted that the actuation of the handle 14 will cause the rail parts 2 to turn and come into alinement with the desired track, and at the same time the hinged rail 6 will be moved into alinement with the same track.

110 It will be noted that the style of the switch here described eliminates the neces-

sity of a special form of cross-over at its joining section. At the same time, this style of cross-over reduces the amount of material required for crossings, and also is arranged so that it may be readily changed or repaired whenever the same is desirable. There are many other advantages apparent to those skilled in the art.

It is of course understood that any suitable means may be used for supporting the drum 15, the handle 14 and the other parts usually used in connection therewith. Fig. 2 shows a preferred form of construction for this portion of the device.

Having thus described this invention, what is claimed is:—

In combination with a railway switch having points hinged to both sides of the rails of a track, cross-overs, a frog comprising

a relatively large flat plate, a rail member 20 pivotally secured to the central portion of said plate, said member having dove-tailed grooves adjacent to the ends thereof, a pair of dove-tail members disposed on and secured to said plate and adapted to fit into 25 said grooves and guide said members transversely across said plate, and means for actuating said rail member, substantially as described.

In testimony whereof we hereunto affix 30 our signatures in the presence of two witnesses.

WILLIAM F. HAMPTON.
CHARLES W. HAMPTON.
